WALDEN L. LASKEY, OF NEW YORK, N. Y., ASSIGNOR TO AMERICAN CAN COMPANY,
OF NEW YORK, N. Y., A CORPORATION OF NEW JERSEY.

SLIP-COVER CAN.

1,073,859.

Specification of Letters Patent. Patented Sept. 23, 1913.

Application filed March 3, 1911. Serial No. 612,044.

To all whom it may concern:

Be it known that I, WALDEN L. LASKEY, a citizen of the United States, residing in New York, in the county of New York and State 5 of New York, have invented a new and useful Improvement in Slip-Cover Cans, of which the following is a specification.

My invention relates to improvements in sheet metal cans of the kind having slip 10 covers.

The object of my invention is to provide a slip cover can suitable for use in shipping oysters or other articles or products, which will have provision for very securely locking or holding the cover on the can and also provision for tightly closing or sealing the can to protect its contents against contamination, and which will be of a simple and efficient construction, capable of being 20 cheaply manufactured and which also may be conveniently opened.

My invention consists in the means I employ, and herein shown and described to practically accomplish this object or result, 25 the same consisting essentially in a slip cover can, the body of which is furnished at its mouth end with an external annular shoulder, preferably formed by an internal bead, and the slip cover of which has its 30 flange provided with an internal annular shoulder preferably formed by an internal bead on the flange of the cover and an encircling locking wire band surrounding the flange of the slip cover and having a contractible loop therein for contracting the flange of the cover about the mouth of the can to lock the cover on the can and to cause 35 it to produce a tight closure. The flange of the cover has a notch therein for the contractible loop of the wire band to project 40 through, and it is also preferably furnished with one or more further notches or slits to enable the flange of the cover to expand and contract when the wire band is loosened or 45 tightened.

In the accompanying drawing forming a part of this specification, Figure 1 is a central, vertical section of a slip cover can embodying my invention. Fig. 2 is a horizontal section on line 2—2 of Fig. 1. Fig. 3 is a detail plan view showing the wire band before the contractible loop therein is pinched together to contract the flange of the cover and close it upon the can body. 55 Fig. 4 illustrates a modified construction in

which the meeting ends of the wire band are secured together by hooks or loops instead of being soldered or welded together as shown in Figs. 1 and 2. Figs. 5, 6, 7 and 8 are detail vertical sections showing a number of different modified constructions of the interengaging annular shoulders on the can body mouth and cover flange respectively.

In the drawing, 1 represents the body of a 65 slip cover sheet metal can of large size or several gallons' capacity, such as is commonly used for shipment of oysters.

2 is the bottom head of the can secured to the body in any suitable manner. 70

The sheet metal body 1 of the can is preferably provided near its upper end with the customary external annular bead 3 to stiffen the same, and with a mouth portion 4 above said bead, preferably terminating in an internal annular roll 5 at the extreme upper end. The mouth portion 4 of the can body is also furnished with an external annular cover locking shoulder 6, preferably formed by an internal annular bead 7, which produces an external annular groove in the can body. 75

The slip cover 8 has a depending contractible and expansible flange 9, which is provided with an internal locking shoulder 85 10 adapted to register with and engage the external locking shoulder 6 on the can body when the cover flange 9 is contracted. The cover flange 9 is also preferably furnished with a flange or roll 11 which embraces the 90 contractible wire band 12, which is furnished with a contractible-integral loop 13 to facilitate the tightening of the wire band after the cover has been applied to the can body. The meeting ends of the wire from 95 which the wire band 12 is formed, are preferably joined by a welded, brazed or soldered joint 14, as illustrated in Figs. 1 and 2. They may, however, be connected by hooks or loops 14^a formed upon the ends of 100 the wire, as illustrated in Fig. 4.

The cover flange 9 is furnished with a notch or cut away portion 15 for the loop 13 of the contractible wire band to project through, and it is also preferably provided 105 with one or more further slits or notches 16 to facilitate the contracting and expanding of the cover flange.

In the modification illustrated in Fig 5, the external annular locking shoulder 6^a on 110

the can body is shown as being formed by an external annular roll at the extreme upper end of the can body, and the internal locking shoulder 10^a on the cover flange is produced by the underhanging of the cover flange 9 when it is contracted by the wire band 12, as will be readily understood from the dotted lines in this figure.

In the modification illustrated in Fig. 6, 10 the external annular locking shoulder 6 on the can body is of the same construction as shown in Fig. 1, but the internal annular locking shoulder 10^b on the cover flange is formed by an internal annular roll 11^b at 15 the extreme lower edge of the cover flange.

In the modification illustrated in Fig. 7, the external annular shoulder 6^c on the can body is produced by outwardly flaring the mouth portion 4^c of the can body and the 20 internal annular locking shoulder 10^c on the cover flange 10 is produced by contracting the cover flange through the agency of the wire band 12.

In the modification shown in Fig. 8, the 25 construction is similar to that shown in Fig. 1, excepting that the cover flange is left with a straight depending portion 17 below the internal bead or annular shoulder 10, and the wire band 12 is thus not permanently secured to the cover flange, as in the 30 constructions illustrated in the other figures of the drawing.

In operation, after the can has been filled, 35 the slip cover is applied to the can body, and then with a pair of pincers or other suitable implement, the integral, contractible loop 13 in the wire band 12 is contracted or pinched together from the form shown in Fig. 3 to the form shown in Fig. 2, thus 40 contracting the slip cover flange of the cover and causing the same to form a tight closure with the can body, and also to be very securely locked in position thereon so that it cannot be removed without severing 45 the wire band or opening up the contracted loop 13 so as to loosen the cover flange on the can body.

It will be noted that the can body and 50 cover both being made of sheet metal, are adapted to be contracted when the loop in the wire band is pinched together, and after the loop has been formed the can body and cover will expand more or less to take up any slack which may be remaining in the 55 band.

I claim:—

1. In a slip cover can, the combination 60 with a sheet metal can body having an external locking shoulder, of a slip cover having a depending flange furnished with an internal locking shoulder adapted to engage the external locking shoulder on the can body, and a contractible wire band provided with a loop and surrounding the flange of 65 the slip cover and contained within a curled

portion of the flange, said flange of the slip cover having a notch therein for said loop to project through, substantially as specified.

2. In a slip cover can, the combination 70 with a sheet metal can body having an external locking shoulder, of a slip cover having a depending flange furnished with a locking shoulder adapted to engage the external locking shoulder on the can body, and a contractible, stiff, bendable band surrounding the flange of the slip cover, said band having an integrally formed contractible loop therein, the members of which are adapted to be pinched together to tighten 75 the band, said can body being adapted to be contracted when the loop is pinched together, and to expand and take up the slack in the band after the loop has been formed.

3. In a slip cover can, the combination 80 with a sheet metal can body having an external locking shoulder, of a slip cover having a depending flange furnished with an internal locking shoulder adapted to engage the external locking shoulder on the can body, and a contractible wire band having 85 a contractible loop and surrounding the flange of the slip cover, said depending flange of the cover having a curved flange adapted to retain the wire band in place, 90 substantially as specified.

4. In a slip cover can, the combination 95 with a thin sheet metal can body, of a thin sheet metal slip cover having a thin sheet metal depending flange embracing the upper end of the can body, and a contractible metal band encircling the flange of the cover, and having an integral contractible loop therein, said band being adapted to 100 lock and tighten the cover on the can body and cause it to produce a tight closure there-with when the loop is pinched together, substantially as specified.

5. In a slip cover can, the combination 105 with a sheet metal can body having an external locking shoulder, of a slip cover having a depending flange furnished with an internal locking shoulder adapted to engage the external locking shoulder on the can body, and a contractible wire band having a contractible loop and surrounding the flange of the slip cover, said depending flange of the cover having a curved flange adapted to retain the wire band in place, 110 said curved flange being provided with a plurality of 115 slits therein on its exterior, whereby the same is adapted to easily bend when the wire band is contracted, substantially as specified.

6. In a cover sealing means for sheet metal 120 cans, the combination with a can having an external locking shoulder near the top edge of the body portion, of a sheet metal slip fit cover having a depending flange provided with a curled portion, a contractible band 125 130

having a compressible loop projecting from said cover flange so arranged that when said cover is placed on the can and the projecting loop is compressed, the wire band is caused to contract, whereby the cover flange is resiliently held in locking engagement with the external locking shoulder of the can, and whereby, when the encircling wire

band is severed, the restrained resilience of the can body and cover flange is released, **10** thereby permitting easy removal of the slip cover, substantially as specified.
